[57] CLAIM

The ornamental design for a cuvette for a chemical analyzer, as shown and described.

DESCRIPTION

FIG. 1 is a perspective view of a cuvette;
FIG. 2 is a top view;

FIG. 3 is a side elevational view thereof, the opposite side elevational view being identical thereto;

FIG. 4 is a bottom view;

FIG. 5 is a cross-sectional view thereof, taken along the line 5—5 of FIG. 2;

FIG. 6 is a right hand end view; and,

FIG. 7 is a left hand end view.
